[57] **CLAIM**

The ornamental design for a combined stand, mirror and charging unit for dry shavers, as shown and described.

DESCRIPTION

FIG. 1 is a perspective view showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dotted line showing throughout the drawing figures is included for the purpose of illustrating features of my design which are seen through transparent material.
